UNITED STATES PATENT OFFICE.

FELIX VOGEL, OF ALTONA, GERMANY.

SHOE-STRETCHER.

1,101,221.

Specification of Letters Patent. Patented June 23, 1914.

Application filed November 18, 1913. Serial No. 801,640.

To all whom it may concern:

Be it known that I, FELIX VOGEL, a subject of the German Emperor, and a resident of Altona-on-the-Elbe, Germany, have invented a new and useful Shoe-Stretcher, of which the following is a specification.

The object of the invention is a stretcher for shoes or boots.

In the drawing a form of construction of the stretcher is represented.

Figure 1 shows a perspective view of the stretcher, being in the interior of a boot, shown by dotted lines. Fig. 2 shows a front view of the stretcher and the boot is shown in dotted lines.

The stretcher consists of a wooden angular piece *a* of suitable form and size. On this wooden piece an arm *b* is pivoted by a hinge *c*. The wooden piece *a* possesses a series of notches *d*. A frame *e* made of wire, having coils *e*¹ and a handle *e*², arranged on the exterior of the shoe, serves to press the bottom or sole of the boot upwardly; whereas the lower end of arm *b* and the lower end 25 of the wooden piece *a* press, in the interior

of the boot, the front and back part of the boot downwardly. In this manner the boot remains in a stretched position and the folded leather retains its original form without folds. The coils *e* serve to render the wire elastic and the series of notches *d* can be used for regulating the pressure of the wire frame *e*.

I claim:

A stretcher for shoes, comprising in combination, an angular wooden piece arranged to be positioned in a shoe and having an upper end provided with a series of notches, an arm pivoted to the rear face of said upper end, and a frame of elastic wire having a plurality of coils, the frame being arranged to surround the exterior of a shoe and to engage the sole with its lower middle portion and the upper middle portion of said frame arranged to engage one of said notches.

FELIX VOGEL.
